UNITED STATES PATENT OFFICE.

EVERETT P. LARSH, OF DAYTON, OHIO, ASSIGNOR TO THE BURNETT-LARSH MANUFACTURING COMPANY, OF DAYTON, OHIO, A CORPORATION OF OHIO.

OPERATING MECHANISM FOR CUT-OUTS.

1,248,505.

Specification of Letters Patent.

Patented Dec. 4, 1917.

Application filed February 12, 1916. Serial No. 78,082.

To all whom it may concern:

Be it known that EVERETT P. LARSH, citizen of the United States, residing at Dayton, in the county of Montgomery and State 5 of Ohio, have invented certain new and useful Improvements in Operating Mechanism for Cut-Outs, of which the following is a specification.

My invention relates to quick acting me- 10 chanical cut outs or control devices adapted to actuate an electric switch, open or close a valve, shift a clutch into or out of operative engagement, or perform other analogous operations under the influence of variations of 15 pressure, temperature, or intensity of an actuating medium.

In the principal figures of the drawing the apparatus has been shown in a form 20 adapted to operate an electric switch under the influence of variations in fluid pressure. In other figures of the drawing the apparatus is illustrated in form to be controlled by variations of temperature, by thermo- 25 static means or by variations of fluid level as by means of floats.

In the form shown in the principal figures of the drawing the apparatus is particularly 30 adapted for use in controlling the motor driven supply pump of private water systems. In the installation of such water systems it is customary to store water and air in a suitable tank or reservoir by means of 35 a motor driven supply pump under sufficient pressure that the water may be discharged through the pipe lines of the distribution system by the influence of the air pressure within the tank or reservoir. Control or 40 cut out devices have heretofore been applied in conjunction with such systems which are intended to maintain the pressure within 45 prescribed limits by setting the supply pump in operation when the pressure within the tank and distribution system falls below a predetermined pressure and to arrest the supply pump when the pressure has been restored to a predetermined degree.

In many instances these control devices 50 have been of a slow acting type which are objectionable inasmuch as they tend to gradually open or close the switch, valve or other operated member in proportion to variations of pressure. Much difficulty has been experienced by the tendency of such devices to come to rest in a partially oper-

ated condition. The actuating medium to 55 the motor is thus reduced to such extent as to be insufficient to properly operate the motor before the pressure within the tank is sufficient to produce a full or complete stroke of the cut off device. Under such 60 conditions the motor actuating medium may continue to flow which in the case of an electric motor not only results in loss of current but may result in serious deterioration 65 of the motor coils and in the case of a fluid pressure motor would result in a waste of water, air or other operating medium.

The object of the present invention is to 70 simplify the structure as well as the means and mode of operation of such devices whereby these difficulties and disadvantages will be overcome and the device not only 75 cheapened in construction but will be more efficient in use, positive in operation, sensitive, and unlikely to get out of repair.

A further object of the invention is to 80 provide quick operating means for positively imparting to the operated element a full or complete movement or stroke at such operation.

Further object of the invention is to provide improved means for completing the movement of the parts after such parts have been initially set or operated by the variation of pressure, temperature, or intensity 85 as hereinafter described.

With the above primary and other incidental objects in view, as will more fully appear in the specification, the invention consists of the features of construction, the 90 parts and combinations thereof, and the mode of operation, or their equivalents, as hereinafter described and set forth in the claims.

Referring to the drawings, Figure 1 is a 95 side elevation of the assembled apparatus constructed to open and close an electric circuit by variations of fluid pressure. Fig. 2 is a vertical sectional view of the assembled apparatus under a condition of low pressure 100 wherein the electric circuit or switch is closed. Fig. 3 is a similar view of the parts in operated position under a condition of high pressure by which the switch is operated to open or break the circuit. Fig. 4 105 is a top plan view of the operating mechanism. Figs. 5, 6, 7, and 8 are detail views of the operative parts. Fig. 9 is a side ele-

vation somewhat diagrammatic of the operative mechanism actuated by a float under influence of variations of fluid level. Figs. 10 and 11 illustrate two modes of controlling the apparatus by variations of temperature. Fig. 12 is a detail view of the application of the device to a valve. Fig. 13 is a plan view somewhat diagrammatic of the electric switch illustrating the wiping contact of the switch parts. Fig. 14 is a detail view of the application of the apparatus to a shifting clutch.

Like parts are indicated by similar characters of reference throughout the several views.

In constructing the device there is employed a main frame comprising a hollow or chambered base 1 from which project upwardly parallel side plates 2-2 connected one with the other by tie bars 3-3. The base 1 is preferably formed in separable parts between which is clamped a flexible diaphragm 4. Spaced feet or supports 5 are provided on the base adapted to rest upon a table or bed plate and a centrally disposed screw threaded projection or nipple 6 is adapted to project through a suitable opening in the table or bed plate and receive a lock nut on the under side thereof. A passage 7 for the fluid under pressure leads to the under side of the diaphragm 4.

Resting upon the upper side of the diaphragm 4 and movable vertically in unison with the undulations of the diaphragm is a stem or shaft 8 having at its upper end a sliding bearing in a bushing 9 screw threaded into a transverse bar or head 10 extending between the plates 2-2. Adjacent to its lower end the stem or shaft 8 is provided with a head or collar 11 upon which is engaged one end of a helical tension spring 12, the opposite end of which bears upon the under face of the bushing 9. The spring 12 tends to resist the upward reciprocation of the shaft or stem 8 whereby the operation of the apparatus is prevented until the fluid pressure upon the diaphragm 4 becomes sufficiently great to overcome the tension of the spring 12. The tension of the spring 12 may be varied by screwing the bushing 9 a greater or less distance into the transverse bar or head 10.

Located below the collar or head 11 and connected thereto by means of a yoke 13 is a second head 14 having a sliding bearing in an opening 15 in the upper face of the base 1. A bearing plate 16 is engaged with the lower extremity of the stem or shaft and distributes the weight of the shaft or stem and pressure of the spring 12 over a large area of the diaphragm.

Fulcrumed upon a transverse pin 17 engaged in the side plates 2-2 is a bell crank 18, the short arm of which carries a roller 19 engaging within the yoke 13 of the stem

or shaft. The yoke is provided with bearing surfaces engaging the upper and lower sides of the roller 19 whereby any vertical variation of the shaft or stem 8 under the influence of increased pressure on the under side of the diaphragm 4 or the influence of the spring 12 upon decrease of pressure is transmitted to the bell crank 18 oscillating the latter about its fulcrum pin 17. Projecting laterally from the bell crank 18 is a stud or pin 20 projecting into a hole 21 of greater diameter than the pin in the side plate 2. The engagement of the stud or pin 20 with the opposite sides of the hole 21 limits the oscillation of the bell crank in either direction.

At its upper edge the long arm of the bell crank 18 carries a roller 22 which extends within the bifurcation 23 of the second bell crank 24 fulcrumed upon the transverse pin 25 which is supported in the side plates 2-2. The bifurcation 23 of the second bell crank 24 is somewhat wider than the diameter of the roller 22 whereby there will be a limited degree of lost motion between said parts. The longer arm of the second bell crank 24 is also bifurcated as at 26 and extending across such bifurcation and mounted in the fingers of said arm is a rock shaft or pin 27.

Fulcrumed upon a transverse pin 28 supported in the side plates 2-2 is a cut out arm 29. In the drawing, particularly in the detail view Fig. 7, this cut out arm has been shown in the form of a double bell crank the pendent arms of which are connected transversely one with the other as at 30 and support a pendent lug 31 to which the operated element such as the electric switch, the valve or other member may be connected. One of the arms 29 carries a projecting stud or pin 32 extending within an enlarged opening or hole 33 in the side plate 2. The oscillation of the cut out arm is limited by the engagement of the pin 32 with the opposite side of the hole or opening 33.

The employment of the holes 21 and 33 in the side plates 2 to form limiting stops for the movable parts results in a considerable economy of manufacture. Heretofore it has been customary to cast lugs or projections upon the frame parts or upon the movable parts of such apparatus to form such limiting stops. However, more or less machine work must be resorted to in order to accurately locate or surface such stops. In the present instance the holes 21 and 33 are drilled in the side plate 2 at the same time that the holes for the fulcrumed pins 17, 15 and 28 are drilled. Such holes are all located with the same drilling gig whereby the relation of the stops and the fulcrum points is constantly maintained. Likewise, the holes for the stop pins 20 and 32 are located by means of a drilling gig

simultaneously with the location and drilling of the holes for the fulcrum pins 17 and 28 in the levers 18 and 2. This feature of construction while seemingly simple results 5 in a considerable saving in the cost of manufacture and furthermore is conducive to greater accuracy.

Pivottally connected intermediate the extremities of the cut out arms 29 is a swinging stirrup 34 from which extends centrally a pin 35 projecting through and reciprocating in an opening 36 in the rock shaft 27 carried by the arm 24. Surrounding the pin 35 and interposed between the stirrup 24 15 at one end and the rock shaft 27 at the opposite end is a helical spring 37 which exerts a pressure upon said parts and tends to turn the cut out arms 29 about its fulcrum pin 28. By changing the direction of the influence of the spring 37, *i. e.*, by oscillating the stirrup 34 and pin 35 whereby the relation of the spring 37 with the arms 29 will be angular either upward or downward according to the direction in which the cut 25 out arm is to be moved, the spring 37 will effect the oscillation of said cut out arm. In the drawings, Figs. 1, 2, 3, there is shown carried upon the lug 31 of the cut out arm a block 38 of fiber or other insulating material to which is attached a transverse arcuate spring 39 carrying at each end contact heads 40. The contact heads 40 are brought 30 into engagement with independent terminal contact studs 41 carried by a block 42 of fiber or other insulating material by the oscillation of the cut out arm 29. The block 42 carrying the terminal studs 41 is attached by means of screws 43 to the main frame of the apparatus. The spring 39 is so proportioned and is held in such relation with 40 the terminal stud 41 when the cut out arm 29 is in inoperative position that upon the oscillation of the cut out arm 29 to close the switch the contact heads 40 will engage the terminal studs 41 before the arm 29 has 45 completed its movement whereby the final movement of the cut out arm subsequent to the engagement of the head 40 with the studs 41 will occur against the tension of the connector spring 39 tending to change the radius of the arcuate spring and thereby force the contact heads 40 one from the other while in contact with the terminal studs 41 thereby causing a wiping action of the head 40 upon the studs 41 which insures a perfect 50 electrical contact and maintains the contact surfaces clean and bright. This relation of the switch members is best illustrated in Fig. 12 in which the normal or open position 60 of the switch is indicated at the top by dot and dash lines, the initial contact position of the switch when the cut out arm is in partially operated position is indicated by solid lines, and the final position being indicated by dotted lines. The movement of

the contact heads 40 after their initial engagement with the terminal studs 41 is indicated by darts.

Operation of the apparatus: It will be noted that the arm 24 comprises one arm of a lever mechanism, the other arm of which consists of the stirrup 34 and pin 35 with the interposed spring 37. The last mentioned lever of the mechanism is a yielding one against the tension of the spring 37 whereby 70 the lever mechanism may be oscillated alternately in opposite directions beyond the dead center. It will be noted that as the lever mechanism thus formed approaches the dead center the spring 37 is placed under 80 tension. The subsequent expansion of the tensioned spring as the lever mechanism is moved to a position beyond the dead center serves to oscillate the cut out arm 29.

Assuming that the parts are in position as 85 shown in Fig. 2 in which the fluid pressure is low and the electrical switch closed, which in the ordinary installation would cause the motor driven pump to be operated to increase the fluid pressure upon the diaphragm, as the pressure increases the diaphragm 4 will be pressed upward causing an upward reciprocation of the stem or shaft 8 against the tension of the spring 12. This upward movement of the shaft 8 is 90 transmitted by the yoke 13 to the bell crank 18 and thence to the arm 24 of the toggle before mentioned. In this operative movement the roller 22 at the upper end of the bell crank 18 bears against the outer side of 95 the bifurcation 23 of the arm 24 thereby tending to oscillate the arm 24 downward. As the arm 24 oscillates downward the distance between the fulcrum point of the stirrup 34 and the rock shaft 27 carried by the 100 arm 24 is gradually shortened. In this shortening movement the pin 35 carried by the stirrup 34 is projected through the opening 36 of the rock shaft 27. This movement of the arm 24 is accomplished against the tension of the spring 37 which is gradually placed under tension as the arm 24 approaches a position of alinement in relation with the axis of the stirrup 34. During 105 this tensioning of the spring 37 the movement of the cut out arm 29 is resisted by the engagement of the pin 35 with the lower side of the opening 33 as indicated in Fig. 1. It will be understood that the movement of the arm 24 from the position shown 110 in Fig. 2 to position in which the axis of the rock shaft 27 is alined with the fulcrum 25 and the axis of oscillation of the stirrup 34 is accomplished gradually and in unison with the gradual increase of pressure upon 115 the under side of the diaphragm 4. During this initial or setting movement of the parts the cut out arm 29 has not varied its position but the circuit switch is maintained closed. As before mentioned, the bifurca- 120

125

130

tion 23 of the arm 24 is slightly larger than the roller 22 whereby there is permitted a limited degree of play or lost motion. A slight movement of the arm 24 beyond the 5 dead center or position of alinement will cause the arm 24 to move quickly under the influence of the compressed spring 37 through the degree of movement permitted by the lost motion or play incident to the 10 enlargement of the bifurcation 23 whereby the spring 37 is moved beyond the dead center very quickly and the direction of its influence is changed whereby the spring exerts an upward pressure upon the stirrup 34 and 15 thereby upon the cut out arm 29 which by the expansion of the spring 37 is suddenly oscillated upward within the limits prescribed by the hole 33 in the plate 2. This oscillatory movement of the cut out arm 29 20 under the influence of the spring 37 serves to disengage the contact heads 40 and terminal studs 41 as shown in Fig. 3. The parts remain in their operated position as shown in Fig. 3 so long as the fluid pressure 25 on the under side of the diaphragm 4 is sufficient to overcome the tension of the spring 12. However, as the pressure decreases the spring gradually forces the stem or shaft 8 downward, thereby oscillating the bell 30 crank 18 which acts upon the arm 24 through the bifurcation 23 in the reverse direction, tending to again aline the lever mechanism, before mentioned, against the tension of the spring 37 until the position 35 of alinement or dead center is reached whereupon the lost motion or play incident to the enlargement of the bifurcation 23 permits the arm 24 to pass beyond the dead center independent of the bell crank 18 whereupon 40 the force of the compressed spring 37 is exerted downward and the subsequent expansion of the spring 37 serves to oscillate the cut out lever 29 to return the contact head 40 into engagement with the terminal 45 studs 41.

It will be seen that the apparatus is set or initially operated in one direction by the preponderance of fluid pressure on the under side of the diaphragm 4 which exceeds 50 the tension of the spring 12 and in the opposite direction by the preponderance of the tension of the spring 12 over the fluid pressure. However, the fluid pressure and spring actuate the parts only throughout 55 their initial or setting movement. The cut out arm 29 is quickly oscillated in both directions by the subsequent expansion of the spring 37. This action of the arm 29 is accomplished by changing the abutment of 60 the spring 37 from the point below the operative connection with the cut out arm to a point above the connection with the cut out arm and vice versa.

In Fig. 9 there is illustrated a modification wherein a vertically movable float 44

connected by a link 44' to an extension 45 of the arm 24 is employed in lieu of the diaphragm 4 and bell crank 18. The mechanism and operation is otherwise as before described. In the construction shown in 70 Fig. 9 the cut out arm 29 is controlled by variations of fluid level. As the float 44 rises the arm 24 will be oscillated downward, thereby compressing the spring 37 (not shown in this figure) which in turn 75 will oscillate the cut out arm 29 in the manner before described. Upon a downward movement of the float 44 the operation of the parts will be reversed. The said parts will be actuated through such reverse operation either by the weight of the float 44 which will pull downward upon the arm 45 or by means of a spring similar to the spring 12 before mentioned which may be employed in conjunction with the weight 44. In Fig. 80 85 10 there is shown in lieu of the bell crank 18 a thermostatic bar 46 preferably composed of strips of material possessing different degrees of expansion whereby the excess of expansive force of one material over that 90 of the other will tend to warp the thermostatic bar as indicated by dotted lines in said figure. The thermostatic bar 46 carries at its upper end a roller 47 corresponding to the roller 22 of the primary construction 95 which operates in the bifurcation 23 of the arm 24 in the manner before described. Thus an excess of temperature will cause the thermostatic bar 46 to warp in one direction and thereby oscillate the arm 24 to reverse 100 the cut out arm 29 while a decrease of temperature will through contraction of the thermostatic bar operate the parts in reverse direction. However, a spring such as the spring 12 may be employed to return the 105 parts.

In Fig. 11 there is illustrated a construction embodying the bell crank lever 18 previously described to which is connected a thermostatic rod 48 which by its expansion 110 and contraction under varying degrees of temperature tends to oscillate the bell crank 18 to operate the parts in the manner before described. The cut out arm 29 may be connected to a clutch lever 51 by which a clutch member 52 may be thrown into and out of 115 engaging position as indicated in Fig. 14.

While the cut out arm 29 has been shown in Figs. 1, 2 and 3 provided with electrical switch contacts, it is obvious that in lieu of 120 the electrical connection the cut out arm 29 may be connected to the stem 49 of a valve 50 as indicated in Fig. 12. Thus the apparatus may be made to seat and unseat the valve 50.

From the above description it will be apparent that there is thus provided a device of the character described possessing the particular features of advantage before enumerated as desirable but which obviously 130

is susceptible of modification in its form, proportion, detail construction, or arrangement of parts without departing from the principle involved or sacrificing any of its 5 advantages.

While in order to comply with the statute the invention has been described in language more or less specific as to certain structural features, it is to be understood that the invention is not limited to any specific details but that the means and construction herein described comprise but one mode of putting the invention into effect and the invention is therefore claimed broadly in any of its 10 possible forms or modifications within the scope of the appended claims.

Having thus described my invention, I claim:

1. In a device of the character described, 20 the combination with a member to be operated of a movable actuating member therefor; a lever mechanism controlling said movable actuating member, and means for oscillating the members of the lever mechanism 25 in opposite directions to alternate the movement of the actuating member.

2. In a device of the character described, the combination with a member to be operated of a movable actuating member therefor, 30 a lever mechanism, a spring placed under tension by the operation of the lever mechanism adapted to move said actuating member, and means for operating the lever mechanism to tension the spring.

3. In a device of the character described, 35 a member to be operated, a movable actuating member, an actuating spring therefor, a movable abutment for said spring and means for shifting the said movable abutment in relation to the point of application 40 of the spring with the actuating member whereby the spring will alternately operate said member in opposite directions.

4. In a device of the character described, 45 a member to be operated, a movable actuating member, an actuating spring therefor, a swinging support for the spring adapted by its movement to cause the spring to act in different directions upon the actuating 50 member to move said member in different directions and means to shift said swinging support.

5. In a device of the character described, 55 a member to be operated, a movable actuating member therefor, a lever mechanism controlling said actuating member one link of which is resilient, means for oscillating the lever mechanism whereby said resilient link is placed under tension, the actuating 60 member being moved by the subsequent reaction of the resilient link.

6. In a device of the character described, 65 a member to be operated, a movable actuating member, a lever mechanism the members of which are slidingly connected one

with the other, an operating spring for said actuating member placed under tension by the relative movement of the lever mechanism, and means for operating the lever mechanism.

70

7. In a device of the character described, a helical actuating spring, two relatively movable abutments for said spring, means for moving one of the spring abutments thereby placing the helical spring under 75 tension, the subsequent reaction of which will serve to move the second abutment, and cutout means actuated by the movement of the second abutment.

8. In a device of the character described, 80 two independently movable arms capable of oscillatory movement to and fro beyond positions of alinement one with the other, a spring interposed between the free ends of the arms placed under tension by the relative movement of the arms as they approach a position of alinement, adapted by its subsequent reaction to actuate said arms beyond a position of alinement, means for actuating one of said arms substantially into a 90 position of alinement with the other arm, and cutout means actuated by the movement of the second arm.

85

9. In a device of the character described, a movable cutout, an actuating member, a 95 lever mechanism controlling said member, means for initially operating said lever mechanism toward a position of alinement or dead center, and means for imparting to the lever mechanism an additional movement beyond dead center independent of the initial actuating means, said actuating member being operated by said additional movement.

100

10. In a device of the character described, 105 a movable cutout, an actuating member, a lever mechanism controlling the movement of the member, means for operating the lever mechanism to cause it to approach a position of dead center, and means placed 110 in operative condition by the approach of the lever mechanism toward dead center for actuating the lever mechanism beyond the dead center position and thereby imparting movement to the actuating member.

115

11. In a device of the character described, a movable cutout, an actuating member, a lever mechanism controlling the movement of the member, means for operating the lever mechanism to cause it to approach a position of dead center, and means placed in operative condition by the approach of the lever mechanism toward dead center for imparting movement to the actuating member independent of the lever mechanism operating means.

120

12. In a device of the character described, a movable cutout, an actuating member, a lever mechanism controlling the movement of the member, means for operating the le- 130

ver mechanism to cause it to approach a position of dead center, there being a limited degree of lost motion or play between the said operating means and the lever mechanism whereby the toggle will be permitted a limited movement beyond position of dead center independent of the operating means, and means for imparting motion to the actuating member by the movement of the lever mechanism.

10 13. In a device of the character described, two oscillatory arms extending each toward the other, a resilient link connecting the free ends of the arms, means for oscillating one of the arms thereby tensioning the resilient link, said link being adapted by its reaction to move the second arm, and a cut-out connected to the second arm.

14. In a device of the character described, 20 two oscillatory arms extending each toward the other, a helical spring interposed between the free ends of the arms and abutting on each arm, means for moving one arm to change the relation of the spring abutments whereby the spring will act upon the second arm in a different direction, thereby oscillating said arm and a cut out connected thereto.

15. In a device of the character described, 30 a member to be operated, a movable actuating member therefor, means for imparting movement to the actuating member, a control lever one arm of which is bifurcated controlling said means, and a vibratory operating member engaging in the bifurcation of the control lever.

16. In a device of the character described, a member to be operated, a movable actuati-

ing member therefor, means for imparting movement to the actuating member, a control lever controlling said means, and a vibratory operating member operatively engaged with the control lever by a loose connection whereby one of said members will be capable of a limited movement independent of the other member.

17. In a device of the character described, a main frame, a member to be operated, a movable actuating member therefor, means for imparting movement to the actuating member, 50 a movable control member and a variable operating member operatively connected with the control member, and means for limiting the degree of movement of the operating parts comprising a stud on the member to be limited engaging in a drill hole in the main frame.

18. In a device of the character described, a main frame, a member to be operated, a movable actuating member, means for imparting movement to the actuating member, means for setting the movement imparting means in operative condition, a stud carried by a movable member of the combination, said frame having a hole drilled therein of greater diameter than the stud, the opposite sides of which form limiting stops determining the degree of movement of the member.

In testimony whereof, I have hereunto set my hand this 9 day of February A. D. 1916.

EVERETT P. LARSH.
